INVENTOR.

Charles W. Hubbard,

UNITED STATES PATENT OFFICE.

CHARLES W. HUBBARD, OF PITTSBURG, PENNSYLVANIA.

DESIGN FOR AN AX.

SPECIFICATION forming part of Design No. 20,771, dated May 26, 1891.

Application filed January 19, 1891. Serial No. 378,360. Term of patent 14 years.

To all whom it may concern:

Be it known that I, CHARLES W. HUBBARD, of Pittsburg, in the county of Allegheny and State of Pennsylvania, have invented a new and original Design for Axes, of which the following is a full, clear, and exact description, reference being had to the accompanying drawings, forming part of this specification, in which—

10 Figure 1 is a plan view of an ax embodying my design. Fig. 2 is a vertical longitudinal section thereof on the line II II of Fig. 1.

15 The leading feature of my design consists in an ax-head which back of the cutting-edge is made laterally concave toward the butt, and at the middle of the ax there is no longi-

tudinal convex wedge-shaped ridge, as common in axes of the designs heretofore known. This concavity extends completely across each side of the ax-body.

20 In the drawings, 2 represents the cutting-edge; 3, the eye of the ax-head, the sides of which are concave, as shown in Fig. 2.

I claim—

25 The design for axes, substantially as herein shown and described.

In testimony whereof I have hereunto set my hand this 15th day of January, A.D. 1891.

CHARLES W. HUBBARD.

Witnesses:

THOMAS W. BAKEWELL,

H. M. CORWIN.
